UNITED STATES PATENT OFFICE

HERMAN PRIES, OF MICHIGAN CITY, INDIANA.

REFRIGERATOR-CAR.

939,315.

Specification of Letters Patent. Patented Nov. 9, 1909.

Application filed June 21, 1909. Serial No. 503,406.

To all whom it may concern:

Be it known that I, HERMAN PRIES, a citizen of the United States, and resident of Michigan City, county of Laporte, and State 5 of Indiana, have invented certain new and useful Improvements in Refrigerator-Cars, of which the following is a specification, and which are illustrated in the accompanying drawings, forming a part thereof.

10 The invention relates to that class of refrigerator cars in which the partition separating the body of the car into a storage and an ice compartment is removable for the purpose of permitting the utilization of the 15 entire interior of the car for storage purposes.

The invention consists in the novel features hereinafter pointed out relating to the construction of the partition, the means for 20 securing it in position, and the means for providing for its removal and storage when not in service; and it consists further in a structure such as is hereinafter described and as illustrated in the accompanying 25 drawings, in which—

Figure 1 is a vertical cross-section of the body of a car showing the partition in elevation; Fig. 2 is a detail longitudinal vertical section of the car; Fig. 3 is a detail 30 plan section thereof showing a supporting roller for carrying the partition when not in service; Fig. 4 is a detail perspective of the floor of the car showing the rest for the lower end of the partition when in service, 35 some of the parts being broken away; Fig. 5 is a detail plan section of the side wall of the car and of the supporting latch for carrying the partition when not in service; and Fig. 6 is an elevation of the latch and its 40 casing shown in Fig. 5.

Certain sills of the car are shown at 10, and its floor at 11. At 12, 13, there are shown the side walls, and at 15 the roof of the car.

45 The partition for separating the car into its two compartments comprises a framework consisting of a plurality of upright bars 16, 17, the former being as numerous as may be desired, and the latter constituting the ends of the frame; and a plurality 50 of cross-bars 18. The inner face of the partition, that is to say, the face presented to the ice, comprises a plurality of cross-slats 19, spaced apart to permit circulation 55 of air between the two compartments. There

has been described a conventional form of partition, but the invention is applicable to a partition of any preferred construction.

The table for supporting the ice comprises the longitudinal bars 20 and 21, the former 60 being shown as of wood and the latter a metal Z-bar; and a plurality of cross-bars 22. This floor is hinged, as represented at 23, to the end of the car, and its free end is supported by legs 24, as many being employed as may be required, three being represented in the drawings, these legs being pivoted to the Z-bar 21 so that they may be swung upwardly when the floor is folded against the end of the car to the dotted lines 65 70 position of Fig. 2. A gravity latch 25 is shown as pivoted to the end of the car for engaging the Z-bar 21 when the floor is raised.

The lower end of the partition is prefer- 75 ably armored with an angle bar 26, which, when the partition is in service, is seated in a chair formed of a plurality of straps 27 folded over and gained into a cross-sill 28, secured to the floor of the car. The inner 80 end of each of the straps 27 is upturned, as shown at 29, to form a stop to hold the partition against inward movement. The top of the sill 28 is armored by means of a metal plate 30, which slightly overhangs the inner 85 face of the sill and abuts against the up-standing leaf of the angle bar 26.

At its upper end the partition bears against a pair of rollers (only one of which is shown), as 31, journaled upon studs 32, 90 setting through and projecting beyond the inner face of the wall of the car, these rollers being spaced apart from the car roof a sufficient distance to permit the partition to slide over them when its lower end is swung 95 forwardly into the storage compartment of the car. In order to protect these rollers from injury by the ice, each is covered by means of a stout sheet metal hood 33, carried by the partition. The upper end of the 100 partition is held against forward movement, when in service, by any suitable means. For this purpose there is shown a plurality of gravity latches 34, pivoted to the upper cross rail of the partition and entering sockets, as 105 35, formed in the under face of a cross-beam 36 of the car.

When not required for service the partition is stored in the top of the car, in the dotted lines position shown in Fig. 2. To 110

raise it to this position the latches 34 are first disengaged from their sockets, the partition is then raised out of engagement with the plate 30 and its lower end swung upwardly in the storage compartment, the partition then being pushed back upon the rollers 31 until its upper edge abuts against the end of the car and rests upon a cross-beam 37. Its lower end is engaged by a pair of latches (only one of which is shown), as 38, projecting inwardly from the side wall of the car. As shown, each of these latches is carried by an upright pivot 39, set within a chambered casing 40, secured to the side wall of the car, into the chamber of which the latch may be swung to permit the partition to be raised above it. In order that the latch may be returned to its operative position by gravity, it is shown as being provided with a beveled flange 41, which engages a beveled floor 42 of the casing 40. When the latch is pushed back into the chamber of the casing, these beveled members raise it by a cam action and by a similar action swing it outwardly when it is released.

Various details of construction may be deviated from without departing from the scope of the invention, which broadly consists in means provided for carrying the partition when out of service and holding it securely in the position of service.

I claim as my invention—

1. In a refrigerator car, in combination, a body, a movable partition for dividing the body into two compartments, stops projecting from the walls of the body for engaging the partition at one side thereof and adjacent its upper end, such stops being spaced apart from the top of the body, means for staying the partition on the side opposite the stops, and an additional support attached to the body coöperating with the stops to carry the partition in a substantially horizontal position.
- 45 2. In a refrigerator car, in combination, a body, a movable partition for dividing the body into two compartments, studs projecting inwardly from the body walls adjacent the tops thereof and engaging one face of the partition, and an additional support for the partition when raised to a substantially

horizontal position and moved back on the studs.

3. In a refrigerator car, in combination, a body having instanding studs adjacent the tops of its side walls, a movable partition for dividing the body into two compartments, such partition bearing against the studs and being slideable thereon when raised to a substantially horizontal position.

60 4. In a refrigerator car, in combination, a body having instanding studs adjacent the tops of its side walls, a movable partition for dividing the body into two compartments, such partition bearing against the studs and being slideable thereon when raised to a substantially horizontal position, and a latch secured to the body and engaging the partition when raised.

65 5. In a refrigerator car, in combination, a body having instanding studs adjacent the tops of its side walls, a movable partition for dividing the body into two compartments, such partition bearing against the studs and being slideable thereon when raised to a substantially horizontal position, and a gravity latch secured to the body and movable into a pocket in the wall thereof and adapted to engage the partition when raised.

70 6. In a refrigerator car, in combination, a body, studs projecting inwardly from the side walls thereof adjacent their tops, a sill crossing the floor of the car, a movable partition having one of its faces in contact with the studs and its opposite face engaging the sill, lugs rising from the floor of the body engaging the partition to hold it against the sill, and latches engaging the partition and a portion of the body to hold the partition against the studs.

75 7. In a refrigerator car, in combination, a body, a movable partition for dividing the body into two compartments, a chair on the floor of the body for receiving the partition, studs projecting inwardly from the side walls of the body adjacent their tops for engaging one face of the partition, and latches for holding the partition against the studs.

95 HERMAN PRIES.
